UNITED STATES PATENT OFFICE.

JOHN H. GEARY, OF CHICAGO, ILLINOIS.

DESIGN FOR A MILITARY-SERVICE BUTTON.

58,311.

Specification for Design.

Patented July 12, 1921.

Application filed November 27, 1918. Serial No. 264,456. Term of patent 7 years.

To all whom it may concern:

Be it known that I, JOHN H. GEARY, a citizen of the United States, residing at Chicago, in the county of Cook and State of Illinois, have invented a new, original, and ornamental Design for a Military-Service Button, of which the following is a specification, reference being had to the accompanying drawing, in which—

Figure 1 is a plan view of a button embodying my design, and Fig. 2 is an edge view of the button.

I claim:—

The ornamental design for a military service button, as shown.

In testimony whereof I affix my signature.

JOHN H. GEARY.
